INKING APPARATUS

John Duke Tyler, Birmingham, Ala.

Application September 20, 1937, Serial No. 164,725

24 Claims. (Cl. 101—344)

This invention relates to inking apparatus for a printing press of the reciprocatory bed type, and has for an object the provision of a unitary assembly which can be mounted and dismounted from the printing press as a whole by a single latch control.

A further object of the invention is the provision of inking mechanism including a multiplicity of rollers in which the rollers may be separated for cleaning and protection without individual removal from the assembly.

A still further object of my invention is the provision of a simplified mechanism for oscillating certain of the rollers.

Another object of my invention is the provision of a simplified fountain with means for adjusting the ink flow from the fountain whereby the degree of adjustment may be noted visually.

Another object of my invention is the provision of a fountain which, with its feed roller, can be removed as a unit from the assembly.

In accordance with my invention, the printing press in which the inking mechanism of my invention is mounted, is provided with frame members in which the inking mechanism is adapted to fit. The inking mechanism fits readily into assembled relation with the frame members of the printing press, and a simple latch control secures the inking mechanism relatively to the press. The rollers of the inking mechanism are supported by roller bearings which rest in matching slots of the frame of the inking mechanism. The slots are so arranged that when an inner frame is raised, the rollers are separated for protection and for cleaning.

Included in my improved mechanism are a plurality of oscillating rollers. The intermediate oscillator rollers are provided with bevelled ends which bear against flanges of the trucks of others of the rollers, whereby the oscillator rollers are caused to oscillate upon rotation. A large oscillator roller included in the assembly is oscillated by means of a ball and race mechanism responsive to rotation of the roller.

All of the rollers of the assembly are adapted for limited vertical movement in their frame, and this vertical movement is utilized to provide for the ink feed. The fountain with its feed roller is preferably made as a separable unit from the rest of the assembly and is mounted for removal independently of the other rollers. An operating mechanism, preferably of the ratchet and pawl type is carried by the fountain and is operated by relative movement of the other rollers to operate the fountain feed roller.

These and other features of my invention are illustrated in the accompanying drawings forming a part of this application, in which

Fig. 1 is a side elevation of a printing press having my improved inking mechanism applied thereto;

Fig. 2 is a sectional view taken along the line II—II of Fig. 1.

Fig. 3 is a sectional view taken along the line III—III of Fig. 2;

Fig. 4 is a side elevation of the assembly removed from the printing press;

Fig. 5 is a side elevational view of the inner roller supporting frame removed from the assembly;

Fig. 6 is a front view of the ink fountain;

Fig. 7 is a side elevational view of the same;

Fig. 8 is a detail view showing means for effecting oscillatory movement of the large oscillator roller; and

Figs. 9, 10 and 11 are sectional views, somewhat diagrammatic, illustrating the operation of my improved inking assembly with a combined type form and stencil.

Referring to the drawings, I show a printing press having a reciprocatory bed 10 driven by a sprocket chain 11 having a pin 12 fitting into a yoke 13. The sprocket chain is driven from a motor 14 through a belt 16, and a train of gears 17. At 18 is shown an impression roller, or platen, which is mounted in a frame 19 for reciprocatory vertical movement in response to movements of the bed 10, and is well understood with this type of printing press and which forms no part of this present invention. On the bed 10 is a side rail 21 which serves to actuate the inking rollers of the assembly as the bed reciprocates back and forth beneath them.

The inking roller assembly may be attached and removed as a unit from the frame of the printing press, being secured thereto by a single latch control. Referring to Fig. 2 of the drawings, the frame of the printing press is shown at 22 projecting upwardly on each side. Pins 23 are carried by the frame and extend inwardly thereof near the upper surface of the reciprocatory bed 10. In each of the upper portions of the frame members 22 there is provided a recess 24. The inking roller assembly is mounted in outer side frame members 26 having in each at the bottom a notch 27 to fit over the pins 23. The outer side frame members 26 are joined together by a top horizontal member 28, through which extends a regulating screw 29 having a regulating nut 31 and a lock nut 32 thereon.

Pivoted on the shaft of the screw 29 beneath the cross member 28 is an arm 33 having a manually controlled handle 34 connected thereto intermediate its ends and having connected to its ends links 36 and 37, which are coupled at their outer ends to pins 38 and 39, which are adapted to fit into the recesses 24. Whenever it is desired to mount the assembly in the printing press frame, the notches 27 are placed over the pins 23 and the main side frame is swung to position 10 where the pins 38 and 39 are in alignment with the recesses 24, whereupon the arm 33 is swung around to move the pins into the recesses 24 and to lock the assembly in position.

The inking mechanism consists of a fountain 41 with the usual flexible blade 42 and feed roller 43 which is supported as a unit between the side frame members 26 on guides 44 fixed to the side frame members. It bottoms against end stops 46, also secured to the side frame members, and is held in place by means of latch pins 47 which extend into suitable recesses in the side frame members 26. The blade 42 can be adjusted to any desired clearance with respect to the feed roller 43 by means of a plurality of eccentrics 48 each having a handle 49 thereon for rotating it around a shaft 51. Each of the eccentrics is preferably made of resilient spring metal and is bored slightly smaller than the shaft 51 upon which it fits, and is provided with an open notch 52 which permits it to spread when mounted on the shaft 51 and engage the shaft with sufficient frictional contact to hold it in any angular position it may be placed. The eccentrics 48, as will be seen from Fig. 6, are mounted side by side on the shaft 51 so as to effect control of the space between the blade and the feed roller 43 throughout the length of the blade.

The feed roller 43 is mounted in the sides of the fountain 41 and is operated by means of a pawl and ratchet mechanism 53 from an arm 54. As the arm 54 is raised and lowered in a manner to be described later, the feed roller 43 is turned by the ratchet in a clockwise direction, as seen in the drawing, to take the ink from the fountain 41.

The distribution of the ink after leaving the fountain 41 is brought about by a plurality of distributing and oscillating rollers. A pickup roller 56 contacts the feed roller 43 and takes the ink therefrom, from which it goes to a large oscillating roller 57 which bears by gravity against the pickup roller 56 and against a distributing roller 58, which in turn contacts with a rider oscillating roller 59 which bears against the form contact roller 61, which latter comes in contact with the printing form on the bed 10 when the press is in operation. A rider roller 62 also takes the ink from the roller 58 and carries it to a distributing roller 63, which contacts with a second rider oscillator 64 and the latter contacts with a form contact roller 66. The rollers 56, 58, 63, 66 and 61 are made of composition ink roller material, while the rollers 57, 59, 64 and 62 are made of metal. The roller 56 is mounted on a shaft 67; the roller 58 on a shaft 68; the roller 61 on a shaft 69; the roller 62 on a shaft 71; the roller 63 on a shaft 72; the roller 64 on a shaft 73; and the roller 66 on a shaft 74.

Mounted on the ends of the shaft 74 are friction trucks 76 which bear upon the upper rail 21 of the reciprocating bed 10. Also on the ends of the shaft 69 are friction trucks 77. A shaft 78 extending across beneath the pickup roller 56 carries on its ends friction trucks 79 which ride 75

on the rails 21 of the reciprocating bed and engage with friction rolls 81 at the ends thereof to give motion to the pickup roller 56. The oscillator 57 is driven by frictional contact with the rollers 56 and 58 from their respective trucks 77 and 79.

All of the shafts of the rollers and trucks just described are mounted in bearings carried in the side members 82 and 83 of an inner skeleton frame which fit within and bear against the side members 26 of the outer frame. There are three rows of bearings in each side member. Each of the three bearings in the upper row is designated by the numeral 84; those in the middle row by the numeral 86; and those in the bottom row by the numeral 87. All of the bearing housings, as shown in Fig. 5, have flat sides which extend through vertical guide slots 88, 89 and 91 in the outer side frame members 26 so that the said bearings are freely movable vertically in said guide slots. The said bearing housings also extend through matching, short, vertical slots in the vertical skeleton side frame members 82 and 83. The upper row of bearings 84, as shown in Fig. 5, extend through short vertical slots 92, the intermediate bearings through short vertical slots 93, and the lower bearings through short vertical slots 94.

By reference to Fig. 5, it will be seen that the bearings 84 are nearly to the bottom of the slot 92, the bearings 86 have slight clearance between them and the bottom of the slots 93, while the bearings 87 have more clearance between them and the bottom of the slots 94. This is the working position of the rollers, so that as the trucking rollers at the bottom of the assembly are rotated, their frictional contact with the rollers above them drive those rollers. The roller 62 rotates on a shaft 71 which extends through the outer frame member 26, and is also cradled in slots 97 formed in the inner skeleton frame members 82, 83. When the rollers are in working position, as described, there is a slight clearance between the ends of the shaft 71 and the bottoms of the slots 97. This clearance is so arranged that upward movement of frame members 82 and 83 will first lift roller 62 relatively to rollers 58 and 63.

The bearings 87 are biased downwardly by means of springs 85 which are held in the skeleton end frame members 82 and 83. The upper catch roller 56 is biased downwardly by means of coil springs 90 bearing against the housings for its bearings 84 to insure contact with the feed roller 43.

From the description of the assembly already made, it will be seen that if the inner skeleton side frame members 82 and 83 be lifted vertically, the roller 62 will first be lifted clear of contact with the rollers 63 and 58 as above described. The bearings for the rollers 63, 58 and 56 will then be raised by reason of the bottom of the slots 92 engaging with the bearings 84 so that the top row of rollers will be raised clear of the intermediate row; the bearings for the rollers 64 and 59 and friction rollers 81 will next be picked up by engagement of the bottom of the slots 93 with their respective bearings; and the bearings 87 will next be picked up by the bottom of the slots 94 engaging therewith, so that the rollers will all be picked up separately and separated so that the entire assembly can be cleaned without disassembling or taking out any one of the rollers, except the loosely mounted rollers 62 and 57. The skeleton side frame members 82 and 83

are joined together by an upper cross member 98 to which the adjusting screw 29 is integrally joined. A spring 99 on the adjusting screw 29 bears against an adjustable collar 101 on the screw and against a collar 102 beneath the cross member 28 to regulate the downward pressure of the skeleton side frame members 82 and 83. If the adjusting nut 31 be screwed down the skeleton side frame members 82 and 83 are lifted bodily to separate the rollers. If the adjusting nut 31 be screwed up, the skeleton side frame members 82 and 83 are pushed downwardly by the spring 99 to bring the rollers together. The extent to which the side frame members can be pushed down is determined by the setting of the lock nut 32. This permits adjustment of the travel of the side frame members 82 and 83 to compensate for variation in diameters of the rollers due to expansion and contraction and wear.

Mounted on the skeleton side frame members 82 and 83, are vertical lugs 103 and 104 (Fig. 2) having vertical slots 106 therein which are adapted to receive a shaft 107 for the oscillator 57. The shaft is flattened at 108 where it enters the slots 106 so as to hold it against rotation, the oscillator 57 being adapted to rotate about the shaft 107. Mounted rigidly on the shaft 107 within the oscillator 57 is a member 109 (Fig. 8) having formed therein a ball race 111 which is continuous about the member 109 so as to form a reverse pitch helical groove. A ball 112 rides within the groove 111 and is confined in a recess in a ring 114 mounted on rods 116 and 117 extending through the length of the roller inside and secured in end plates thereof by means of nuts 118. The ball 112 is held in proper pressure relation to the groove and recess by means of a set screw 113. As the roller 57 is rotated by frictional engagement with the rollers 56 and 58, the ball 112, travelling in the groove 111, moves the roller back and forth longitudinally with considerable travel, there being a complete oscillation to and fro for each revolution of the oscillator roller 57.

The rider oscillating rollers 59 and 64 are oscillated from the trucks 16 and 17 by means of flanges 119 and 121 provided for said trucks. The rollers 59 and 64 are duplicates in construction and the details of the oscillating means are shown only in Fig. 2 with respect to the oscillating roller 64. By reference to that figure, it will be seen that the ends of the roller are bevelled at 122 and 123 with parallel surfaces and that they bear against the flanges 119 of the trucks 16. As the trucks 16 rotate, the distributing roller 66 rotates the oscillating roller 64 by frictional engagement therewith and as oscillator 64 rotates, bearing against the flanges 119 causes it to oscillate longitudinally.

In the operation of the printing press, the side rails 21 of the reciprocating bed 10 pass from beneath the trucks 16, 17 and 18, each time the bed reciprocates, allowing vertical movement of the bearings 84, 86 and 87 in their respective slots. Also, the inner frame members 82 and 83 are free to reciprocate vertically a distance determined by the setting of the lock nut 32. The arm of the ratchet and pawl mechanism 54, when the ink fountain is in place, extends between the bearings 84 and 86, so that the vertical reciprocating motion of the bearings and the inner frame is transmitted to the pawl and ratchet mechanism to cause the feed roller 43 to rotate and carry ink to the pickup rollers 56.

The skeleton frames 82 and 83 bear against

rollers 124 mounted on the side frames 22 to prevent cramping of the bearings in the registering slots of the inner frame and outer frame during relative movement of the two frames.

The inking assembly is adapted also for co-operation with a combined printing and stenciling operation. The inking rollers, as before stated, are adapted to be driven from the trucks 16, due to the frictional engagement of the trucks with the side rails 21 of the reciprocating bed 10. In Figs. 9, 10 and 11, I show a stencil unit 126 and a type set up 127 which are locked in the bed 10 in any suitable manner known to the art, not shown. The stencil unit is provided with side rails 128 which are inside the side rails 21 of the bed 10, so that as the flanges 119 of the truck 66 (and the flanges of other trucks) reach the side rails 128, they lift the inking rollers clear of the mimeograph assembly. When this occurs, the inking of the mimeograph stencil is taken care of by other means not shown.

From the foregoing description, the operation of my improved inking apparatus will be apparent. As the bed 10 reciprocates, the friction trucks 16, 17 and 18, in contact with the rails 21, effect rotation of the rollers 56 to 66, inclusive. As the bed 10 approaches the end of its travel to the left, as seen in Fig. 1, it passes out from beneath the friction trucks and all of the rollers are permitted to move downwardly to the bottom of the slots for their respective bearings. When the bed moves to the right, they are again raised. This vertical reciprocatory movement of the rollers operates the ratchet and pawl mechanism 53, 54, and effects rotation of the feed roller 43 to carry ink to the pickup roller 56. The ink picked up by the roller 56 is distributed over the rollers 63 and 68 by the oscillator 57 and the rider roller 62. The intermediate oscillators 59 and 64, having bevelled ends bearing against the flanges of the friction trucks, are oscillated as they rotate, thus further distributing the ink over the form contact rollers 61 and 66.

The amount of ink to be fed to the particular parts of the form is regulated by the adjustment of the eccentrics 48 on the shaft 51. The angle of the eccentric can be visually noticed by the position of the handles 49.

The ink fountain with the feed roller can be removed from the assembly for cleaning by simply unlatching the latches 41. The large oscillator 57 can be removed by lifting it out of the slots 106. If desired, it may be placed with the ends of the shaft 107 in a slot 130, as shown in Fig. 4, which raises it out of contact with the rollers 56 and 58, or the position shown in Fig. 3.

The whole assembly can be removed from the printing press by releasing the latches 38 and 39 by means of the handle 34 and lifting it out of the printing press. The rollers may be separated by screwing down on the adjusting nut 31 to bring the rollers to the position shown in dotted lines in Fig. 4. With the rollers thus separated, they can be cleaned without being individually removed from the frame.

As shown in Figs. 9, 10 and 11, the flanges on the friction trucks make it possible to utilize my improved inking mechanism in association with the stenciling operation, the flanges being adapted to ride up over the rails 128 provided on the stenciling frame, thus raising the inking roller off the stencil. By this arrangement, a combined printing and stenciling operation may be carried out simultaneously.

While I have shown my invention in but one

form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:

1. In an inking roller assembly for a printing press, form rollers, a plurality of distributing rollers disposed above the form rollers, roller shafts, bearings for the shafts, an outer relatively fixed position frame for the rollers having elongated vertical slots therein for the superposed bearing housings, an inner frame having separate relatively short vertical slots for the several superposed bearing housings, said slots registering with the slots of the outer frame, the bottoms of the upper of said slots being nearer their respective housings than the bottoms of the lower slots, and means to raise the inner frame whereby to separate the rollers.

2. In an inking roller assembly for a printing press, a plurality of rollers including lower form rollers and superposed distributing and oscillator rollers, bearings for the rollers, a frame having vertically aligned slots for supporting the respective superposed roller bearings, means responsive to movements of the printing press to effect reciprocatory movement of at least certain of the roller bearings in their slots, a fountain roller, and means responsive to reciprocatory movement of the said roller bearings to effect rotation of the fountain roller.

3. In an inking roller assembly for a printing press, a plurality of rollers including lower form rollers and superposed distributing and oscillator rollers, bearings for the rollers, inner and outer relatively movable frames having aligned slots in which the bearings are mounted for vertical movement, the slots of the inner frame being relatively short, and the bottoms of the upper of said slots being nearer their respective bearings than the bottoms of the lower slots, and means for raising the inner frame to separate the rollers.

4. In an inking roller assembly for a printing press of the reciprocatory bed type, a plurality of rollers including lower form rollers, superposed distributing and oscillator rollers, an ink fountain with its fountain roller, means responsive to movement of the reciprocatory bed to effect vertical reciprocatory movement of at least certain of the rollers, and means responsive to said vertical reciprocatory movement to effect rotation of the fountain roller.

5. In an inking roller assembly for a printing press of the reciprocatory bed type, a plurality of rollers including lower form rollers and superposed oscillator and distributing rollers, side rails on the bed, frictional drive trucks coacting with the rails to rotate the rollers, beveled ends on the oscillator rollers, and flanges on the trucks bearing against the beveled ends of the oscillator rollers to oscillate the same.

6. In an inking mechanism, a form roller, an oscillating roller bearing upon the form roller and having parallel beveled ends, driving means for the form roller, and flanges on the driving means bearing against the bevelled ends of the oscillating roller.

7. In an inking mechanism for a printing press, the combination of a form roller, an oscillating roller bearing against the form roller, parallel

bevelled ends on the oscillating roller, a supporting truck for rotating the form roller, and means on said supporting truck adapted to bear against the beveled ends of the oscillating roller to oscillate it longitudinally as it rotates.

8. In an inking mechanism for a printing press of the reciprocatory bed type, including a plurality of distributing and form contact rollers and means to drive the rollers, an ink fountain with its feed roller, a pickup roller contacting with the feed roller, a distributing roller associated with the pickup roller, a large oscillator roller bearing on the distributing roller and the pickup roller, a fixed shaft extending through the oscillator roller, a sleeve disposed within the oscillator roller intermediate the ends thereof and rotatable therewith, and a ball and race connection between the shaft and the sleeve whereby the roller is oscillated as it is rotated.

9. In an inking mechanism for a printing press of the reciprocatory bed type, including a plurality of distributing and form contact rollers and means to drive the rollers, an ink fountain with its feed roller, a pickup roller contacting with the feed roller, a distributing roller associated with the pickup roller, a large oscillator bearing on the distributing roller and the pickup roller, a fixed shaft extending through the oscillator roller, a sleeve disposed within the roller intermediate the ends thereof and rotatable therewith, a member carried by the shaft having an inclined continuous ball race formed therein, and a ball carried by the sleeve to contact with the race and effect oscillation of the roller as it is rotated.

10. In an inking mechanism for a printing press of the reciprocatory bed type, including a plurality of distributing and form contact rollers and means to drive the rollers, means responsive to reciprocation of the bed to effect a limited vertical movement of the rollers, side frame members in which the rollers are mounted, an ink fountain with its feed roller mounted in the side frame members adjacent the rollers, a pawl and ratchet mechanism for rotating the feed roller, and an arm for the pawl and ratchet mechanism connected with the rollers to effect operation of the pawl and ratchet in response to vertical movement of the rollers.

11. In a printing press, in combination, vertical side frame members, side frame members for an inking assembly fitting within the side frame members of the press, a cooperating pin and notch connection between the lower parts of said side frame members, and a latch for engaging the upper parts of said members.

12. In an inking roller assembly for a printing press, rollers adapted to rotate in contact with the printing form, a series of supply and distributing rollers superposed above the form rollers, bearings for the rollers, an outer relatively fixed frame having elongated vertical slots in which the bearings are slidably mounted, an inner frame member having registering shorter slots for the bearings of each roller, the bottoms of the shorter slots being nearer the bearings of the upper rollers than the lower, and means to raise the inner frame relative to the outer.

13. An inking roller assembly for a printing press of the reciprocatory bed type including a series of rollers horizontally and vertically arranged to distribute ink, means mounting at least certain of said rollers for vertical movement relatively to the plane of said reciprocatory

bed, a fountain roller in contact with at least one of said rollers for initiating the distribution of the ink by said rollers, a reciprocating bed movable relatively to said rollers and adapted to move at least certain of said rollers vertically on said mounting means, and means operable by the said vertical movement of said rollers for rotating said fountain roller.

14. In an inking mechanism for a printing press of the reciprocatory bed type, including a plurality of distributing and form contact rollers and means to drive the rollers, means responsive to reciprocation of the bed to effect a limited vertical movement of at least certain of the rollers, an ink fountain having a feed roller, a pawl and ratchet mechanism for rotating the feed roller, and an arm for the pawl and ratchet mechanism connected with the rollers to effect operation of the pawl and ratchet in response to said vertical movement of the rollers.

15. In an inking roller assembly for a printing press of the reciprocatory bed type, a plurality of rollers including lower form rollers and superimposed oscillator and distributing rollers, side rails on the bed, trucks for said form rollers coacting with the rails, beveled ends on the oscillator rollers, and flanges on the trucks bearing against the beveled ends of the oscillator rollers to oscillate the same.

16. In an inking mechanism, a form roller, an oscillating roller bearing upon the form roller and having parallel beveled ends, supporting trucks for the form roller, and flanges on the supporting trucks bearing against the beveled ends of the oscillating roller.

17. In an inking mechanism for a printing press, the combination of a form roller, an oscillating roller bearing against the form roller, parallel beveled ends on the oscillating roller, a reciprocating bed having side rails, means for rotating the form rollers on said side rails, and means associated with the said means to bear against the beveled ends of the oscillating roller to oscillate it longitudinally as it rotates.

18. An inking assembly including a pair of main side plates, aligned guide slots in said side plates, a series of inking rollers, bearings for said inking rollers mounted for guided vertical movement in said guide slots, certain of said rollers resting on one another when the bearings for said rollers are free to move to their predetermined operating position in said guide slots, a reciprocating type bed, and means on said type bed for moving certain of said rollers vertically with their bearings relatively to said guide slots.

19. An inking assembly including a pair of main side plates, aligned guide slots in said side plates, a series of inking rollers, bearings for said inking rollers mounted for guided gravitational vertical movement in said guide slots, certain of said rollers resting on one another when the bearings for said rollers are free to move by gravity to their predetermined operating position in said guide slots, a reciprocating type bed, and means on said type bed for moving certain of said rollers vertically with their bearings relatively to said guide slots.

20. An inking assembly including a pair of main side plates, aligned guide slots in said side plates, a series of inking rollers, bearings for said inking rollers mounted for guided gravitational vertical movement in said guide slots, certain of said rollers resting on one another

when the bearings for said rollers are free to move by gravity to their predetermined operating position in said guide slots, and movable means juxtaposed to said main side plates for lifting said rollers and their bearings relatively to said side plates and relatively to one another.

21. An inking assembly including a pair of main side plates, aligned guide slots in said side plates, a series of inking rollers, bearings for said inking rollers mounted for guided vertical gravitational movement in said guide slots, certain of said rollers resting on one another when the bearings for said rollers are free to move by gravity to their predetermined operating position in said guide slots, a reciprocating type bed, means on said type bed for moving certain of said rollers vertically with their bearings relatively to said guide slots, and manually operated means for likewise moving said rollers and bearings bodily relatively to said guide slots.

22. An inking assembly including a pair of main side plates, aligned guide slots in said side plates, a series of inking rollers, bearings for said inking rollers mounted for guided vertical movement in said guide slots, certain of said rollers resting on one another when the bearings for said rollers are free to move to their predetermined operating position in said guide slots, a reciprocating type bed, means on said type bed for moving certain of said rollers vertically with their bearings relatively to said guide slots, control plates slidable relatively to said main side plates, surfaces on said control plates adapted to elevate the bearings of said rollers relatively to the main side plates and relatively to one another whereby to separate said rolls, and manual means for moving said control plates simultaneously relatively to said main plates.

23. An inking assembly including a pair of main side plates joined by a horizontal beam member, a latch mechanism for securing said side plates to the printing machine, means for operating said latch mechanism, aligned guide slots in said side plates, a series of inking rollers, bearings for said inking rollers mounted for guided vertical movement in said guide slots, certain of said rollers resting on one another when the bearings for said rollers are free to move to their predetermined operating position in said guide slots, a reciprocating type bed, means on said type bed for moving certain of said rollers vertically with their bearings relatively to said guide slots, connected control plates slidable relatively to said main side plates, surfaces on said control plates adapted to elevate the bearings of said rollers relatively to the main side plates and relatively to one another whereby to separate said rolls, and means on said horizontal beam for lifting said connected control plates simultaneously relatively to said main side plates.

24. In a printing press, in combination, vertical side frame members, side frame members for an inking assembly fitting within the side frame members of the press, means between the side frame members of the inking assembly and the side frame members of the press forming a pin and notch connection, and means on said inking assembly and frame members of the press forming a latch connection for holding the said inking assembly and press assembled at said pin and notch connection.
